THERMOSTATICALLY REGULATED
CIRCULATING SYSTEMWalter A. Geise, Flint, Mich., assignor to General
Motors Corporation, Detroit, Mich., a corpora-
tion of Delaware

Application June 27, 1932. Serial No. 619,400

3 Claims. (Cl. 123—178)

This invention relates to liquid cooled internal combustion engines and, particularly, to the cooling liquid circulating systems of such engines and resides in a cooling liquid circulating system which includes the cooling liquid jacket of the engine, a liquid cooling radiator, a passage through which cooling liquid may be by-passed around the radiator and independently thermostatically operated valves for regulating the flow of cooling liquid through the radiator and the by-passage.

For a better understanding of the nature and the objects of the present invention, reference is made to the following specification in which there is described the preferred embodiment of my invention which is illustrated in the accompanying drawing.

In the accompanying drawing:

Figure 1 is a fragmentary view of an internal combustion engine equipped with a cooling liquid circulating system in accordance with my invention.

Figure 2 is an enlarged fragmentary rear elevation of the upper tank of the radiator shown in Figure 1.

Figures 3 and 4 are fragmentary sections taken, respectively, on the lines 3—3 and 4—4 of Figure 2.

In the drawing, the reference character 10 indicates an internal combustion engine of the liquid-cooled type and the reference character 11 a radiator whose upper and lower tanks 12 and 13 are connected by a core 14 in which there are provided liquid cooling passages between which air is adapted to be drawn by the engine-operated fan 15. In advance of the radiator, there is located a conduit 16 whose lower end communicates with the lower tank of the radiator and whose upper end communicates with the forward end of a tube 17 which extends through the front and rear walls of the upper tank of the radiator.

The lower tank of the radiator is connected to the inlet of the cooling liquid jacket of the engine 10 by a conduit 18 and an engine operated cooling liquid circulating pump 19. To the outlet 20 of the cooling liquid jacket of the engine, there is connected a conduit 21 to which there is connected an elbow 22 in which there is provided a passage 23 which communicates with the tube 17 and a passage 24 which communicates with the passage 23 and an opening 31 in the rear wall of the upper tank of the radiator.

In the passage 23—17, there is located a thermostatically operated valve unit 25 which con-

sists of a tubular housing 26 in which there is pivotally mounted a valve 27 of the butterfly type located within the tube 17 and a thermo-sensitive element 28 of the volatile-liquid-filled expansible and contractible bellows type located in the passage 23 and so connected to the valve 27 by a lever 29 that when the temperature of the thermo-sensitive element increases it tends to close the passage 23—17, and when the temperature thereof decreases it tends to open the passage 23—17.

In the passage 24—31, there is located a thermostatically operated valve unit 30 which includes a valve seat 32 located in the opening 31 and a perforated cage 33 which extends into the passage 24 and to whose end distant from the opening 31 there is fixed one end of a thermo-sensitive element 34 of the volatile-liquid-filled expansible and contractible bellows type whose opposite end is connected to a valve 35 of the poppet type by a stem 36 so that when the temperature of the thermo-sensitive element increases it tends to open the passage 24—31 and when the temperature thereof decreases it tends to close the passage 24—31.

It will be apparent from the foregoing description that cooling liquid withdrawn from the lower tank 13 of the radiator 11 by the pump 19 may, after passing through the cooling liquid jacket of the engine 10, return to the lower tank of the radiator either through the core 14 of the radiator or through the conduit 16. In the former event, the temperature of the cooling liquid entering the lower tank will be considerably lower than that of the cooling liquid leaving the cooling liquid jacket of the engine but, in the latter event, the temperature of the cooling liquid entering the lower tank will not differ appreciably from that of the cooling liquid leaving the cooling liquid jacket of the engine. Whether the cooling liquid which leaves the cooling liquid jacket of the engine will return to the lower tank of the radiator by way of the core 14 or by way of the conduit 16 or in part by way of the core and in part by way of the conduit and, in the latter event, what proportion will return by way of the core and what proportion by way of the conduit, and, consequently, the difference between the temperature of the cooling liquid leaving the cooling liquid jacket of the engine and that of the cooling liquid entering the lower tank of the radiator will depend upon the positions of the valves 27 and 35 and, consequently, upon the temperature of the cooling liquid leaving the cooling liquid jacket of the engine. Since the valves 27 and 35 are oper-

ated by independent thermo-sensitive elements, the position of one of the valves is in nowise dependent upon the position of the other, and, consequently, the flow of cooling liquid through 5 the core will be regulated independently of that through the conduit 16. Obviously, regulation of the flow of cooling liquid through the core independently of that through the conduit makes it possible to control the flow and, consequently, the 10 temperature of the cooling liquid in the cooling liquid circulating system of the engine much more effectively than is possible through the use of a single thermostatically operated valve or by the use of two valves operated by a single thermo- 15 sensitive element. Although it is obvious that if properly calibrated thermo-sensitive elements are used any desired relation between the opening and closing movements of the valves 27 and 35 may be obtained, I consider it preferable, in order 20 to insure that the engine will reach its optimum operating temperature as quickly as possible and will be maintained at this temperature and to maintain the pressure of the cooling liquid in the cooling liquid circulating systems of the engine at 25 a minimum at all times, so to calibrate the thermo-sensitive elements that when the engine is cold the valve 27 will be fully open and the valve 35 fully closed, that the valve 27 will not begin to close until the temperature of the cooling liquid 30 leaving the cooling liquid jacket of the engine is sufficient nearly to fully open the valve 35 and that the valve 27 will not reach fully closed position and the valve 35 fully open when the engine is operating at its optimum operating tempera- 35 ture.

It is obvious that the embodiment of the invention disclosed herein may be modified in various ways, as by using valves and/or thermo-sensitive elements of types different from those 40 shown and described and/or by changing the locations of the thermostatically operated valve units.

I claim:

1. In an internal combustion engine in which there is provided a cooling liquid circuit which includes a cooling liquid jacket, a liquid cooling radiator and a radiator by-passage: a thermostatically operated valve which tends to open as the temperature of the cooling liquid is increased to regulate the flow of cooling liquid through the radiator, and an independently thermostatically operated valve which tends to close as the temperature of the cooling liquid is increased to regulate the flow of cooling liquid through the by-passage. 8

2. The invention claimed in claim 1 in which the second-mentioned valve begins to close only after the first-mentioned valve nearly reaches 9 fully open position.

3. In an internal combustion engine, a cooling liquid jacket, a liquid cooling radiator which includes a core and tanks communicating therewith, a conduit for conducting heated cooling liquid from the jacket to one of the tanks, a conduit for conducting cooled cooling liquid from the other of the tanks to the jacket, a conduit communicating at one end with the first-mentioned 10 conduit, extending through the first-mentioned tank and communicating at the other end with the second-mentioned tank, a thermostatically operated valve which tends to open as the temperature of the cooling liquid is increased as 10 associated with the first-mentioned conduit and the first-mentioned tank to regulate the flow of cooling liquid through the radiator, and an independently thermostatically operated valve which tends to close as the temperature of the cooling liquid is increased associated with the first-mentioned and third-mentioned conduits to regulate the flow of cooling liquid through the 11 third-mentioned conduit. 11
